No. 773,064.

PATENTED OCT. 25, 1904.

U. G. DAUGHERTY.
MANIFOLDING ACCOUNT BOOK.

APPLICATION FILED JAN. 16, 1903.

NO MODEL.

UNITED STATES PATENT OFFICE.

ULYSSES GRANT DAUGHERTY, OF DAYTON, OHIO, ASSIGNOR TO NATIONAL CASH REGISTER COMPANY, OF JERSEY CITY, NEW JERSEY, A CORPORATION OF NEW JERSEY.

MANIFOLDING ACCOUNT-BOOK.

SPECIFICATION forming part of Letters Patent No. 773,064, dated October 25, 1904.

Application filed January 16, 1903. Serial No. 139,250. (No model.)

To all whom it may concern:

Be it known that I, ULYSSES GRANT DAUGHERTY, a citizen of the United States, residing at Dayton, in the county of Montgomery and 5 State of Ohio, have invented certain new and useful Improvements in Manifolding Account-Books, of which I declare the following to be a full, clear, and exact description.

This invention relates to that class of mani- 10 folding account-books which are so constructed as to admit of an entry of certain memoranda upon a single sheet which is retained within the book and at the same time by means of a manifolding sheet or sheets permits a 15 copy or copies of these memoranda to be entered upon a sheet or sheets which are adapted to be detached from the book.

The object of my present invention is to 20 provide a manifolding account and sales book in which certain portions of the memoranda entered upon the original sheet will not be transferred to the duplicate sheet and in which that part of the original sheet which bears these memoranda may be detached and re- 25 tained as a cashier's voucher. Such detached portions of the original sheets may be used to advantage in connection with a cash-regis- ter by depositing them therein as certain special transactions are registered or recorded. 30 For this purpose I employ an original sheet comprising two portions, a main portion and a coupon portion, and this coupon portion is adapted to have entered upon it certain private memoranda for retention by the pro- 35 prietor, and these private memoranda are pre- vented from being transferred to the duplicate sheets by means of a flexible apron or flap of thin material interposed between this coupon and the duplicate sheets.

40 In the accompanying drawings, Figure 1 represents a perspective view of the entire book ready for use. Fig. 2 represents a dia- grammatic longitudinal section of the book.

In the accompanying drawings, A repre- 45 sents the back of the book, which may be of cardboard or any suitable material. Attached

by a flexible hinge *a* to the lower or inner end of this back is a cover B, also of cardboard or suitable material adapted to fold over the front of the book and protect the sheets when 50 not in use. Also attached at the inner end of the back A is a leaf-section C, comprising a number of leaves adapted to receive the original entries and which for convenience may be called the "originals." 55

At the outer end of the back A there is attached a block F, of cardboard or any stiff material of thickness corresponding with the leaf-section C and extending across the entire end of the cover, as shown in Fig. 1. Fas- 60 tened to this outer end of the back A and resting upon the block F is another leaf-section, D, comprising various leaves on which the original memoranda may be duplicated, as hereinafter described. These leaves of the leaf- 65 section D are all perforated at their upper ends near where they are bound together, as at *b*, so that they may be easily detached from the book after the duplication has taken place. Interposed between the two leaf-sections C and 70 D is a support E, which gives greater rigidity to the writing - surface, assists in lifting the leaf-section D, and forms a better support for said leaf-section when the greater part of the leaf-section C has been withdrawn from under- 75neath, which will occur when the book is nearly exhausted. Above the leaf - section D and bound therewith at the outer end is a flexible apron or flap J, of paper or other thin mate- 80 rial, which extends down over a portion of the duplicate leaves D, and above this flap and also attached at the outer end is a mani- 85 folding carbon-sheet G, which extends over the entire length of the duplicate leaf-section D. A binding-strip H, extending across the width of the book, as shown in Fig. 1, is placed over the outer end of the carbon-sheet G. By means of staples *c* this binding-strip H, the carbon-sheet G, the flap J, the leaf- 90 section D, and the block F are all firmly bound together at the outer end of the back A.

As is seen in Fig. 1, the leaf-section D does

not extend the entire length of the book, but is cut off in such a manner as to leave exposed a certain margin d of the leaf-section C, which margin may be used to carry forward the 5 amount of the past account. Each original leaf comprises a main portion M and a coupon portion S, the coupon portion being separated from the main portion by a weakened line or suitable perforations p . Upon the 10 main portion may be written the name of the purchaser, the date, and the details and amount of the transaction. In cases where these books are used as a bookkeeping system wherein each customer is provided with 15 a special book, then the amount of each transaction may be added to the total amount due on previous transactions, and this record of the total amount may be transferred to the next original sheet for reference in carrying 20 forward the amount of past account. The coupon portion S of the original leaf is reserved for whatever private information connected with each transaction the proprietor may wish to retain. Since it is essential that 25 this private information should not be transferred to the duplicate sheets, the flap J is interposed beneath the entire coupon, but between the manifolding-sheet and the duplicate sheet, so that none of the memoranda entered upon the coupon will be transferred to the duplicate sheet, or the flap may be of such 30 length that only a portion of the memoranda upon the coupon will be prevented from transferring to the duplicate sheet, as indicated by 35 the dot-and-dash line x in Fig. 1. That part of the duplicate sheet which is below the flap may be used for printed advertising matter or for some similar purpose. Since this flap J is situated beneath the carbon-sheet G and is 40 concealed from the view of the customer, it is not apparent to the customer that any of the memoranda which is being entered upon the original sheet is not transferred to his own duplicate sheet. Furthermore, the flap 45 does not have to be of heavy material in order to prevent the transfer, which it would have to be if it were situated above the carbon-sheet; but being situated between the carbon-sheet and the duplicate sheet it may 50 be of very thin and flexible material, and a further advantage of this flexibility is obtained in that the flap will naturally bend itself downward, so as always to lie perfectly flat upon the duplicate sheets even though a 55 number of them have been detached from the book at the perforation-line B.

In using the book the total amount of the past account is written upon the margin d of the original page following. Then when the 60 next transaction takes place this next original leaf is withdrawn from under the leaf-section D and is folded over upon the carbon-sheet

G. Then the items of this transaction are entered upon the main portion M and the total of this transaction is added to the past account, ready to be carried forward to the margin d of the following page. At the same time the private memoranda relating to this transaction are written upon the coupon S; but while the memoranda on the main portion M are transferred to the duplicate sheet D through the medium of the carbon-sheet G the memoranda upon the coupon S are not transferred to the sheet D because of the interposition of the flap J. Then the coupon S 75 is detached from the main portion and is retained by the proprietor for his private use, or where this book is used in connection with a cash-register this coupon is placed in the drawer of the cash-register to make a complete record in the cash-register to show that certain goods have been sold on account. The duplicate sheet D is then detached and given to the customer. By this joint coöperation 80 of the coupon S and the flap J the proprietor is enabled to make an entry of his private memoranda in connection with each transaction, may detach these memoranda from the main portion of the original sheet, and does not have these memoranda duplicated upon 85 the customer's slip, and therefore all that remains in the book is a complete summary of the customer's account comprising the same data that is upon the various duplicate slips.

Having thus described my invention, what 90 I claim as new is as follows:

1. In a manifolding account-book, the combination with an original sheet comprising a main part and a coupon part separated by a weakened line, of a duplicate sheet extending 100 under both said main part and said coupon part, a carbon-sheet interposed between said original sheet and said duplicate sheet, and flexible means located beneath both said carbon-sheet and said coupon part but extending 105 only beneath said coupon part to prevent the duplication of memoranda written on said coupon part.

2. In a manifolding account-book, the combination with an original sheet comprising a main part and a coupon part separated by a weakened line, of a duplicate sheet extending 110 under both said main part and said coupon part, a carbon-sheet interposed between said original sheet and said duplicate sheet, and a flexible flap located beneath both said carbon-sheet and said coupon part but extending 115 only beneath said coupon part to prevent the duplication of memoranda written on the coupon part.

3. A manifolding account-book consisting of a lower leaf-pad composed of a plurality of leaves each of which consists of a main part retained within the book, and a detachable

coupon part; an upper leaf-pad composed of a plurality of detachable duplicate leaves; a carbon-sheet extending over the detachable duplicate sheets; and a flexible flap bound together with said duplicate leaves and situated beneath both said carbon-sheet and said coupon part but extending only beneath said coupon part to prevent a duplication of memo-

randa on said coupon part, substantially as described.

In testimony whereof I affix my signature in the presence of two witnesses.

ULYSSES GRANT DAUGHERTY.
